UNITED STATES PATENT OFFICE.

EDWIN S. GUNN, OF LINCOLN, NEBRASKA.

HEADLIGHT.

No. 852,505.

Specification of Letters Patent.

Patented May 7, 1907.

Application filed July 19, 1904. Serial No. 217,256.

To all whom it may concern:

Be it known that I, EDWIN S. GUNN, a citizen of the United States, residing at Lincoln, in the county of Lancaster and State of Nebraska, have invented new and useful Improvements in Headlights, of which the following is a specification.

My invention relates to improvements in headlights, and the object is to provide in connection therewith an illuminated sign and ventilating member, that is simple and inexpensive in construction.

The improvements are particularly useful in association with railway street cars during hours of darkness to announce the direction or destination of the car.

With these purposes in view the invention consists in the novel construction of parts and their aggroupment in operative combination, as will be hereinafter specified and then the novelty asserted will be particularly pointed out and distinctly claimed, as required by the statute.

I have fully and clearly illustrated the invention in the annexed drawings, to be taken as a part of this specification, and reference being had thereto—

Figure 1 is a view in elevation showing the invention as mounted at the front of a street-car, and a designated destination published thereon. Fig. 2 is a vertical central sectional view of the device showing the vertical direction of the rays impinging upon a surface to be illuminated. Fig. 3 is a view in elevation partly in section (below line $x-x$), showing the headlight rays directed to impinge upon the front face of a sign board.

In the drawings the same parts appearing in different figures are designated by the same reference notations.

Reference being made to the drawings, Figs. 1, 2 and 3, 1 designates the usual construction of the one end of a street-car, having the common dash-board 2, to which a headlight 3, is secured. This headlight consists of a conical reflector 4, inclosed in a suitable casing 5, and provided with a lens or glass 6, all of the usual construction, except as follows: The reflector adjacent to its apex 50 has an opening in its under side, as 7, into which a glow-light projects, as 8, the rays of which are directly projected onto the surface of the reflector, and directly thrown into the path of the car, as usual, and in vertical alignment with the aperture 7 is an opening 9, into which the vertically directed rays of

the light are directed, as indicated in Figs. 2 and 3 of the drawings. On the headlight and inclosing the opening 9 with its base, and directly over the light, is positioned a flaring tube or conduit 10, into which the upwardly directed rays are extended to be utilized as means for illuminating a sign mounted on the upper end thereof. The tube 10 it will be seen flares laterally, and the rear portion 65 thereof is continued to form a frame 11, having an open face wherein is disposed a frame 12, whereon are designated such words or symbols as may be required or desired.

It will be readily perceived that the rays of 70 the light projected through the aperture 9 will illuminate anything interposed in their path, as indicated in Fig. 2 of the drawings.

The tubes may be made out of some metal which readily takes a polished surface, or 75 they may be made of some non-corrodible material and then laid with a coat of material which may be burnished.

The flare of the tubes may be varied and tubes of different widths be used to suit the 80 uses required, that is the tubes may be wider or narrower according to the width or length of the surface to be illuminated.

To make manifest the various applications of my invention, it may be stated that, when 85 used in connection with a street car headlight it will throw rays of light on a sign board above the headlight, and thus designate what cars are approaching at night. In this way the expense of a second light is saved, because the same light used as the headlight will reflect enough rays on the sign to make it distinct and readable at least half a block away.

When the device is used in connection with headlights on railroad engines, the rays of 95 light may be turned into vertical space above the engine, so that the illumination can be seen by an approaching train around curves, over small hills, trees or buildings. When so used it will be necessary to use an extra 100 strong light.

When used in connection with the headlight on railroad trains the number of the engine of the train may be distinctly indicated on a suitable surface positioned above the 105 headlight. This will give operators at stations, and train men passing in opposite direction, ample opportunity for distinguishing what train, or what section of a train is passing. This will do away with wrecks caused 110 by trainmen getting confused as to what section has just passed.

By using my device, ordinary sign boards, such as are used in the day time may be used at night without change. The rays from the device being thrown on the letters and not through them, making them much more readily discernible.

Having thus described my invention, what I claim and desire to secure by Letters Patent, is:

10 The combination with a conical reflector formed with oppositely disposed vertically aligned openings, an illuminator extending through one of the openings, and a reflector tube secured in alignment with the other of 15 said openings and extending above the reflector,

tor, said closing outlet from the reflector being of gradually increasing width throughout its length, a sign housing supported by and formed integral with the rear wall of said tube, and a sign receiving frame mounted within the housing and arranged at an inclination to the vertical axis of the tube, the lower end of said frame being in contact with the rear wall of the tube.

20 In testimony whereof, I affix my signature 25 in presence of two witnesses.

EDWIN S. GUNN.
